Application May 14, 1953, Serial No. 354,935

5 Claims. (Cl. 263—19)

The present invention relates to tobacco curing apparatus, and more particularly to an improved apparatus for curing yellow leaf tobacco in an expeditious and positively controlled manner.

In the disclosed embodiment of the tobacco curer, there is provided a heater located outside of the curing barn and enclosed in a casing from which a distributing duct leads to the interior of the barn to convey air and combustion products impelled by a blower in the casing. A pair of return ducts convey the barn air back from the barn to the casing to be circulated again by the blower, and exteriorly of the barn have openings through which outside air may be drawn into the casing by the blower to replace barn air. Dampers to close the openings are provided in the return ducts, so arranged that when the openings are closed the ducts are fully open and unobstructed so that all the barn air is recirculated and none is replaced. The dampers may be moved to block the ducts against passage of barn air while permitting unobstructed movement of outside air through the openings into the casing, or to partially block barn air passage and permit restricted outside air flow through the return ducts. The dampers thus control the proportion of barn air replaced by outside air.

It is an object of the invention to provide apparatus for curing yellow leaf tobacco which affords improved control of all stages of the cure, and produces better results than previous apparatus.

It is another object to provide improved tobacco curing apparatus which employs positive air recirculating means to achieve uniform conditioning of the tobacco and reduction of the time required for curing.

Another object is the provision of improved tobacco curing apparatus incorporating means for accurate control of temperature and humidity conditions to obtain improved cure results.

Another object is the provision of improved tobacco curing apparatus operable at relatively low temperatures to obtain the desired curing temperatures.

It is also an object of the invention to provide improved tobacco curing apparatus incorporating means for controlling replacement of air in the curing barn by outside air in desired proportion.

Another object of the invention is the provision of improved tobacco curing apparatus including means for positively drawing outside air at a controlled rate into the curing barn.

A further object is the provision of improved tobacco curing apparatus including heating means located exteriorly of the curing barn for elimination of fire hazard and accessibility.

Another object is the provision of improved tobacco curing apparatus discharging the products of combustion of the heating means into the curing barn to obtain required barn temperatures with low operating temperatures and eliminate flues and the like.

Still another object is the provision of improved tobacco curing apparatus which employs a single heating means,

2

is compact and simple, is economical to operate and maintain, and achieves better and faster curing than presently used apparatus.

It is a further object of the invention to provide tobacco 5 curing apparatus requiring only intermittent operation of the heating means to obtain necessary temperatures, the frequency and duration of heating means operation being least when greatest humidity is required and greatest when greatest drying effect is desired.

10 Other and further objects, advantages, and features of the invention will be apparent to those skilled in the art from the following description and the accompanying drawings, in which:

Fig. 1 is a vertical sectional view through a tobacco 15 curing barn showing in elevation one embodiment of the apparatus of this invention;

Fig. 2 is a horizontal sectional view through the barn showing the apparatus in plan;

Fig. 3 is an enlarged fragmentary horizontal sectional 20 view through the apparatus;

Fig. 4 is an enlarged vertical sectional view taken substantially as indicated by the line 4—4 of Fig. 3;

Fig. 5 is a vertical sectional view taken substantially as indicated by the line 5—5 of Fig. 4; and

25 Fig. 6 is a detail sectional view illustrating the arrangement for cooling the bearings of the blower shaft.

Apparatus now generally employed for curing yellow 30 leaf tobacco, the type grown in the southeastern United States and requiring the application of heat under varying conditions of humidity for its cure, almost universally comprises no more than a plurality of pot or wick type burners disposed in the curing barn and employing flues or stacks to carry off the products of combustion. High operating temperatures of about 500° F. and often rising 35 to 600° F. are required to obtain the necessary curing temperatures, because of the loss of heat through the flues and also because convection is depended upon for circulation of the air in the barn. The burners lack positive heat control and operate continuously, causing undesirable dissipation of moisture in the yellowing stage of

40 the cure and consuming large quantities of fuel. The high burner temperatures burn out the flues so rapidly that they must be replaced every year, or at most two years, and cause frequent fires the loss from which can 45 be only partially covered by insurance and at high rates because of the frequent incidence. The absence of positive air circulating means not only increases the heat requirements but also tends to lack of uniformity in conditioning of the tobacco and to sweating of the tobacco

50 due to air stagnation. Drying of the tobacco in the later stages of curing is relatively slow due to the relatively haphazard and sluggish gravity circulation of the air. Openings in the walls of the barn having movable covers are provided for admission of outside air when desired,

55 the outside air entering the barn only by convectional effect as the heated barn air escapes. Such prior apparatus is admittedly unsatisfactory being wasteful, inefficient, and hazardous, as well as requiring a relatively long time to effect curing of the tobacco, but heretofore 60 no apparatus effectively solving the problem and remedying the defects has been provided.

The apparatus of the present invention overcomes the difficulties of prior apparatus and provides novel means for the curing of tobacco. In operation, the heater is 65 on only intermittently, and particularly during the earlier portion of the cure for only a minor portion of the time. The blower is operated continuously so that a continuous recirculation of the barn air, including the products of combustion of the heater, is effected, and when desired 70 a closely controlled proportion of this air is replaced by outside air, by manipulation of the dampers. Temperatures and humidity conditions in the barn are readily

maintained close to optimum during all stages of the cure so that the best possible results in curing the tobacco are obtained. The recirculation of the air and the discharge of the combustion products into the barn permit relatively low operating temperatures of the heater, as well as reducing the firing periods required. Together with the disposition of the heater outside the barn, this practically eliminates the fire hazard inherent in the tobacco curing heaters now generally used. Fuel consumption is reduced to only about a third of that of present heaters, maintenance costs are brought to a minimum with the elimination of the flues employed with the present heaters, and the lowering of insurance premiums and fire losses. Only one heater instead of several is necessary, reducing initial outlay. The positive recirculation of the barn air permits more uniform conditioning of all the tobacco and reduces the time required to bring the tobacco to the desired condition in each of the curing stages except the first or yellowing stage, in which it contributes to the desired maximum humidity. Together with the controlled intake of outside air and the moisture-dissipating effect of the heater when burning, the recirculation provides very precise control of humidity in the barn. The shorter curing time required permits a reduction of the number of barns used. Thus the novel tobacco curing apparatus presents many advantages over that now generally used.

Referring to the drawings, there is shown a tobacco curing barn or enclosure B having vent means of ordinary construction in the roof and a door in one wall, with tobacco T racked in the barn in the usual way. Outside of the barn and adjacent one of the walls is a heater casing 10 in the lower part of which a heating flame may be provided by an injection type oil burner 11 supplied with fuel in any desired manner. A burner using fuel other than oil may of course be employed if desired. In the sides and top of the casing there are formed relatively small apertures 12 for a purpose explained hereinafter. In the upper part of the casing 10 is mounted a blower 13 driven by an electric motor 14 through belt and pulley means. The blower is preferably operable at more than one speed, so that the rate of air circulation effected thereby may be varied. A distributing or outlet duct 15 extends from the casing adjacent the discharge or pressure side of the blower and through the barn wall into the interior of the barn, and has a plurality of branch ducts 16 extending therefrom to distribute substantially uniformly about the barn area air and other gases impelled from the casing by the blower 13. The discharge ends of the branch ducts 16 are bent upwardly, and spreader plates 17 are supported slightly above the open ends by angle clips or the like to spread the air laterally as it issues from the branch ducts.

A pair of return ducts 18 opening through the barn wall lead from the interior of the barn to the lower part of the casing 10, on opposite sides thereof, each duct communicating with the interior of the casing through a screened aperture 19 in the casing wall. An intake opening 20 is formed in each return duct exteriorly of the barn wall through which outside air may be drawn into the duct and thus into the casing by the action of the blower 13. A damper 21 is hinged at one side of the opening 20 to swing within the duct 18 between a position closing the opening and a position blocking the duct between its inlet and the opening 20, as best shown in Fig. 3. When the opening is fully closed by the damper 21, no outside air is drawn therethrough and the duct is entirely unobstructed for return flow of air from the barn to the casing and blower, while when the opening is entirely unobstructed by the damper no air is allowed to flow from the barn to the casing through the duct and only outside air is drawn into the casing by the blower, so that all the air in the barn may be replaced by outside air. Such replacement may be continuous, requiring only continued operation of the blower. Replacement of only

a part of the barn air by outside air is readily accomplished by locating the damper intermediate its two extreme positions, the particular position of the damper controlling the proportions of barn and outside air drawn into the casing. The provision of two return ducts leading to opposite sides of the casing 10 affords a balanced flow of air through the casing and to the blower. In the construction illustrated, the ducts each have a right-angled bend between the barn and casing, and the intake opening 20 and aperture 19 are in direct alignment at opposite ends of the run of the duct between the bend and casing, so that the damper 21 may be arranged to swing horizontally 90° between its extreme positions. The arrangement may be varied, however, and the desired result still achieved. The hinged dampers 21 are ordinarily swung to corresponding positions in their respective ducts, but they may be placed in non-corresponding positions if desired, as indicated in Figs. 2 to 4. The dampers 21 are moved manually by means of handles 21a projecting through arcuate slots or other suitable openings in the top walls of the ducts 18, by means of which the damper positions may be ascertained.

To control temperature in the barn B, suitable thermostatic means 22, such as a thermal bulb, is suitably mounted in the barn at an appropriate location and operatively connected to control means 23 mounted outside the barn by which the setting of the means 22 may be adjusted, and through which the burner is turned on and off as hereinafter explained. The burner 11 has a fire pot or combustion chamber 25 within the casing 10, in which the actual combustion of fuel occurs. The combustion chamber may be of any appropriate construction, in this case being shown as a cylindrical pot of sheet metal lined with refractory material. A fuel inlet tube 26 extends from the injection mechanism of the burner through the chamber wall to direct the burning fuel into the chamber. Any suitable igniting means (not shown) may be employed to start burning of the fuel whenever the burner is operated. Within the casing 10 is a cylindrical sheet metal liner 27 extending from adjacent the top of the casing to below the level of the top of the combustion chamber, and spaced from both the casing and chamber. The liner has an external circumferential bead 28 engaging the inner edge of a circularly apertured bottom plate 29 extending between the casing walls and the liner. The outer edge of the plate 29 is formed with a flange which engages in a strip 30 of Z section secured to the inner surface of the casing. The liner 27 is thus supported in the casing by the bottom plate 29 and the bottom of the jacket space between the casing and liner is closed by the plate. The liner has a stepped portion at its upper part cut away as indicated at 31 in Figs. 4 and 5, to accommodate a housing 32 for the blower 13.

The housing has a width corresponding to the length of the blower so that the blower may be received between the side walls of the housing, which are provided with intake apertures 33 providing communication between the interior of the casing and the blower so that air and the products of combustion of the burner 11 may be sucked into the housing by the blower and blown out of the housing and casing into the outlet duct 15 through an outlet 34 of the housing. The housing is supported in the casing by a pair of angle members 35 secured to the housing side walls and fastened at their ends to the front and rear walls of the casing, the upper edge of the liner 27 being slotted to accommodate the flanges of the angle members. A shield 36 is secured to the lower portion of the blower housing in spaced relation to protect it from direct heat. A cover plate 37 closing the major portion of the top of the liner is supported on the angle members. The liner 27, bottom plate 29, and cover plate 37 define a cooling jacket with the casing 10 through which outside air may circ-

culate by means of the apertures 12 and induced by the blower 13. It will be noted that the liner does not fit closely about the housing 32, the wider part of the cut-away portion 31 particularly leaving appreciable openings between the jacket space defined between the liner and casing and between the liner and blower housing. This loose fit is advantageous in facilitating assembly of the housing and blower in the casing and in preventing any possibility of starving the blower. Any air drawn from the jacket by the blower is restricted in volume because of the small size of the apertures 12, and its withdrawal from the jacket enhances the circulation of cooling air therein. Peep-holes 38 and 39 in the top of the casing and in the cover plate 37, respectively, are provided in proper alignment for viewing the combustion chamber 25 whenever it may be desired to determine the condition of the fire.

The blower 13 is mounted on a shaft 40, the ends of which project through apertures 41 (Fig. 6) in the casing side walls and are journaled in suitable bearings 42 supported adjacent the side walls by angle brackets 43 or the like mounted on the walls. The cooling jacket is most effective in preventing heating of the casing 10, the casing remaining cool even when the temperature at the combustion chamber and in the liner 27 is at its greatest, and the bearings 42 are similarly protected from heat radiated from the combustion chamber and liner. By means of the apertures 41, the bearings are further protected from internal heat developed by the rotation of the shaft 40 and from heat conducted by the shaft from the interior of the casing. As the blower rotates with its shaft 40, it sucks air into the casing through these apertures to create air currents which flow past the bearings and cool them, as will be evident particularly from Fig. 6. Thus whenever the blower is operating it is effective to counteract the heating of the bearings due to its operation. The importance of such an arrangement is evident when it is considered that the blower operates continuously throughout the conditioning period of the tobacco. The shaft 40 at one end carries the pulley through which the blower is rotated by the motor 14.

The motor 14 and the motor of the burner 11, as well as the burner ignition means if of the electrical type, are operated by electricity from a suitable source, not shown, to which connection may be made by a cable 45 or the like having a terminal plug or other suitable means for making the connection, and leading to a main switch 46 with which a suitable fuse may be associated. The switch 46 serves also as the control switch for the motor 14, connecting the motor directly to the cable 45 when moved to circuit-closing position and shutting off current to the motor when in circuit-opening position, the motor being connected to the switch 46 by conductors 47. A burner control switch 48 connected to the burner 11 by wires 49 is arranged to place the electrically operated elements of the burner in circuit with the cable 45 through the main switch 46, so that the burner cannot operate unless the switch 46 is closed and the blower operative, even if the switch 48 is closed. A protective relay 50 also controlled by the switch 48 through conductors 51 is connected by wires 52 to the thermostatic control means 23. The relay 50 operates to turn the burner 11 on or off in accordance with the heat requirements in the barn as reflected by the thermostatic means, and also to shut off the burner if a flame is not established upon starting of the burner or if the flame is extinguished during operation of the burner otherwise than in response to the thermostatic means. A limit control 53 is also provided and arranged in circuit with the burner 11 to open the burner circuit and stop burner operation in the event the temperature within the heater casing rises above a predetermined maximum. Alternatively, the control 53 may be

arranged to open the circuit through the main switch 46, so that the blower 13 as well as the burner 11 will be rendered inoperative in the event of excessive temperature within the casing. The several wires and conductors are preferably protected by conduit or the like, in accordance with usual practice. The relay 50 and limit control 53 are of known construction and need not be described in detail.

The apparatus when assembled and installed is operable upon connection to a suitable electrical line, so that upon closing the main switch 46 the motor 14 is started to operate the blower 13. The burner control switch 48 is closed, and if the temperature in the barn is below that called for by the thermostatic means, the control means 23 initiates operation of the burner 11. The dampers 21 are in position closing the intake openings 20 during the first stage of the curing operation, so that all the air in the barn is continuously recirculated throughout the barn uniformly about the tobacco and back through the casing 10 past the combustion chamber 25 and through the outlet duct 15 and its branch ducts 16 into the barn, impelled by the blower. All the products of combustion of the burner are entrained in the recirculating air and aid in heating it rapidly, there being little if any smoke. In the initial or yellowing stage of the curing process, high relative humidity, with relatively low temperature, is necessary to bring about setting of the desired "bright yellow" color in the tobacco before any appreciable drying occurs. Maximum humidity is obtained by the present apparatus because the air is retained in the barn after moving past the tobacco and extracting some of the moisture therefrom so that it is quickly brought close to its saturation point. Because of the recirculation, maintenance of the temperature in the desired range is achieved by operation of the burner for only short periods at infrequent intervals, so that no appreciable "burning off" or dissipation of moisture by the burner flame occurs to lower the humidity. After the yellow color has set, the tobacco is dried and the stems killed, outside air in varying proportions being drawn into the barn by adjustment of the dampers 21 as already explained to reduce the relative humidity, and the temperature within the barn being gradually raised to a maximum by adjustment of the thermostatic control means 23, the blower 13 continuing in operation throughout the process and hastening the drying. The burner operates for a greater proportion of the time, thus aiding in reduction of humidity. After killing of the tobacco stems, which requires a relatively high temperature and the lowest attainable relative humidity, the tobacco is in a very dry condition and therefore so brittle that it cannot be handled without breaking. It is rendered pliable by allowing absorption of moisture from the outside air, which at this stage is more humid than the atmosphere in the barn, and this ordering of the tobacco is accomplished much more rapidly by the present apparatus than by the commonly employed prior means, because the outside air is positively circulated past the tobacco rather than being merely allowed to enter the barn. To accomplish this, the burner is shut off and the dampers 21 are positioned to block return of air from the barn through the ducts 18 and to permit a maximum of outside air to enter through the intake openings 20. Continued operation of the blower draws the outside air through the casing and impels it through the ducts 15 and 16 into the barn to flow in a continuous current past the tobacco, all of the air in the barn being continuously replaced by fresh outside air to bring a constant supply of moisture absorbable by the tobacco. The replaced air also carries off much of the heat of the tobacco, so that both the tobacco and the interior of the barn are cooled sufficiently to allow the barn to be entered and the tobacco removed immediately after it is rendered pliable. The

prior means available for ordering, besides requiring a longer time, did not effect any appreciable lowering of the temperature, so that considerable additional time was required to allow for dissipation of the retained heat of the tobacco before it could be comfortably handled.

While the invention has been disclosed as embodied in the illustrated apparatus, it is to be understood that the disclosed apparatus representing only one possible embodiment of the invention is illustrative in nature.

What is claimed is:

1. Apparatus for curing yellow leaf tobacco racked in a curing barn, comprising a heater casing adjacent the exterior of the barn, intermittently operable heating means having a combustion chamber in said casing, an inner liner providing a cooling jacket at the upper portion of the casing extending below the level of the top of the combustion chamber, a plurality of apertures in the casing for circulation of cooling air through the jacket, a blower above the combustion chamber, a housing for the blower having an inlet communicating with the space about the combustion chamber and an outlet, an outlet duct connecting the housing outlet with the interior of the barn, branch ducts extending from the outlet duct having discharge openings spaced about the barn area, spreader means at said discharge openings to distribute air impelled therethrough from the blower, a pair of return ducts leading from the interior of the barn to opposite sides of the casing for return flow of air through the casing to the blower, an intake opening in each return duct providing communication with the outside atmosphere to admit outside air to the casing, a damper in each return duct adjustably movable between a position closing said intake opening and leaving said duct unobstructed and a position closing the duct against communication between the barn and casing and providing unobstructed communication between said opening and casing to control the ratio of barn air and outside air drawn into the casing, thermostatic means in the barn adjustable from the exterior of the barn for controlling the operation of the heating means in accordance with temperature requirements in the barn, means for preventing operation of the heating means when the blower is inoperative, and means for operating the blower for positive recirculation of air and the heating means products of combustion through the barn and casing, whereby temperature and humidity conditions in the barn are controlled by only intermittent operation of the heating means and replacement of barn air by outside air in desired proportion.

2. Apparatus for heating an enclosure comprising a casing adjacent the exterior of the enclosure, a combustion chamber in one end portion of the casing having an open end for discharge of products of combustion, a fuel burner producing products of combustion in the combustion chamber, a generally cup-shaped sheet metal liner having a closed end wall in the other end portion of the casing and having side wall structure overlapping the discharge end of the combustion chamber and spaced therefrom for receiving products of combustion from the combustion chamber and forming with the inner surface

of the casing a cooling jacket, an inlet duct connected to the interior of the enclosure and opening into the casing for conveying air from the enclosure through the casing and into the liner through the space between the side wall structure of the liner and the combustion chamber for admixture with said products of combustion in a stream in said liner, said duct having a valve-controlled opening to the atmosphere for admitting selected proportions of atmospheric air into said stream, a blower having an inlet in the liner and adjacent the closed end wall thereof for pulling said stream of mixed air and products of combustion from said liner, and discharge duct means for conveying said stream from the blower through the side wall structure of the liner and the casing to the interior of the enclosure, said casing having openings therein opposite the side wall structure of the liner and opposite the closed end wall of the liner for admitting atmospheric air to said cooling jacket, and the intake side of said blower being open to the jacket whereby the fan pulls atmospheric air into the cooling jacket to cool the liner and prevent overheating damage thereto and discharges said air from the cooling jacket into said stream.

3. The combination claimed in claim 2, in which the casing is upright, with the combustion chamber in its lower portion and the liner above the combustion chamber with the closed end wall of the liner in the top portion of the casing, said inlet duct being connected to the lower zone of the enclosure to be heated and to the lower portion of the casing.

4. The combination claimed in claim 2, including a pair of inlet ducts connected to spaced apart portions of the enclosure to be heated and having their discharge ends connected to the casing on directly opposite sides thereof equidistantly apart on opposite sides of the combustion chamber.

5. The combination claimed in claim 2, in which the casing is upright, the combustion chamber is cylindrical and positioned in the lower portion of the casing and the liner is positioned above the combustion chamber with the closed end wall of the liner in the top portion of the casing, and said combination including a pair of inlet ducts connected to spaced apart portions of the lower zone of the enclosure to be heated and having their discharge ends connected to the lower portion of the casing on directly opposite sides thereof and on diametrically opposite sides of the combustion chamber.
